UNITED STATES PATENT OFFICE

143,365

DESIGN FOR A COMBINATION SUBMARINE AND LAND TANK

Robert M. Sutphen, Newark, N. J., assignor to
Couse Laboratories, Newark, N. J., a partnership

Application March 8, 1945, Serial No. 118,360

Term of patent 7 years

(Cl. D14—3)

To all whom it may concern:

Be known that I, Robert M. Sutphen, a citizen of the United States, residing at Newark, in the county of Essex, State of New Jersey, have invented a new, original and ornamental Design for a Combination Submarine and Land Tank, of which the following is a specification, reference being had to the accompanying drawings, forming a part thereof.

In the drawings:

Fig. 1 is a side elevational view of a combination submarine and land tank showing my new design as it would appear with the periscope extended and the antenna retracted.

Figure 2 is a view of the combination submarine and land tank with the tank track extended for running on land and also having the antenna in extended position and the periscope retracted.

Figure 3 is a front end elevational view of Figure 1.

Figure 4 is a front elevational view of Figure 2.

Figure 5 is a vertical cross sectional view on the line 5—5 of Figures 3 or 7.

Figure 6 is a vertical cross sectional view on the line 6—6 of Figure 4.

Figure 7 is a top plan view of Figure 1.

Figure 8 is a bottom plan view of Figure 1.

Figure 9 is a bottom plan view of Figure 2.

Figure 10 is a vertical cross sectional view on the line 10—10 of Figure 1.

Figure 11 is a view on the line 11—11 of Figure 2.

I claim:

The ornamental design for a combination submarine and land tank, as shown.

ROBERT M. SUTPHEN.
